(57) **CLAIM**

The ornamental design for an educational toy as shown and described.

DESCRIPTION

FIG. 1 is a perspective view of an educational toy of the present invention, including a combination of a top part shown in FIGS. 2-8 and a bottom part shown in FIGS. 9-15. FIG. 2 is a perspective view of a top part of the educational toy as shown in FIG. 1;

FIG. 3 is a right view of the top part;

FIG. 4 is a left view of the top part;

FIG. 5 is a front view of the top part;

FIG. 6 is a rear view of the top part;

FIG. 7 is a top view of the top part;

FIG. 8 is a bottom view of the top part;

FIG. 9 is a perspective view of a bottom part of the educational toy as shown in FIG. 1, from which the top part as shown in FIGS. 2-8 has been removed;

FIG. 10 is a front view of the bottom part;

FIG. 11 is a rear view of the bottom part;

FIG. 12 is a left view of the bottom part;

FIG. 13 is a right view of the bottom part;

FIG. 14 is a top view of the bottom part; and,

FIG. 15 is a bottom view of the bottom part.
